NILS D. LEVIN AND ERNST FEODOR MULLER, OF COLUMBUS, OHIO, ASSIGNORS TO THE JEFFREY MANUFACTURING COMPANY, OF COLUMBUS, OHIO, A CORPORATION OF OHIO

BIT-FORMING MACHINE

Application filed April 30, 1926. Serial No. 105,843.

The present invention relates to certain new and useful improvements in bit forming machines, and particularly to machines adapted to form cutter bits suitable for use in the cutter chains of coal mining machines, and similar objects.

In the method of mining coal which is commonly practiced at the present time kerfs, or grooves, are formed in the face of 10 the vein to afford a clearance into which the coal may be moved by blasting, or other suitable means, to break up and dislodge it. These kerfs are commonly cut by tools, known as cutter bits, attached to an endless 15 chain adapted to travel in guideways upon the cutter arm of the mining machine. In such service the points of the bits soon wear off and become dull, and the dull bits must be replaced by sharp ones. This necessi- 20 tates the reshaping and sharpening of large number of cutter bits, and each mine is usually provided with a smithy where such work is performed. Cutter bits formed by hand upon an anvil lack the uniformity of 25 shape and size essential to the economical operation of a mining machine. The satisfactorily operable machines heretofore available for the production of cutter bits have been ponderous affairs only suitable for use 30 in large manufacturing establishments and entailing very considerable initial investment. Numerous attempts have been made to produce relatively small and inexpensive machines adapted to use in the blacksmith 35 shops associated with coal mines. All such machines heretofore constructed, with which we are familiar, possess certain inherent defects which it is the object of this invention to overcome.

It is the especial object of this invention 40 to provide an efficient durable and inexpensive machine, suitable for use in the blacksmith shop associated with the coal mine, whereby accurately formed bits may be conveniently and economically made from new

rolled bar stock, and bits worn in service may be reformed and renewed.

The means whereby we attain this object are fully set forth in the following specification, and illustrated in the accompanying drawings of which

Fig. 1, is a side elevation of the preferred embodiment of our invention.

Fig. 2, is an end elevation.

Fig. 3, is a plan view of the machine 55 shown in Fig. 1.

Fig. 4, is a sectional view taken along line IV—IV of Fig. 2.

Fig. 5, is a sectional view taken along the line of V—V of Fig. 1, showing the die in 60 operative relation with the roll.

Fig. 6, is a fragmentary sectional view taken along the line VI—VI of Fig. 4.

Fig. 7, is a fragmentary sectional view taken along the line VII—VII of Fig. 3. 65

Fig. 8, is a diagrammatic perspective view of the bit marking mechanism.

Fig. 9, is a fragmentary sectional view showing the ejecting mechanism.

Fig. 10 is a perspective detail of the die 70 upon which the bits are formed.

Like numerals refer to similar parts in the several figures.

In the drawings the numeral 1 refers to the main frame of the machine. Journaled 75 in bearings 2 of the main frame 1 is a transversely extending shaft 3 to the projecting end of which is fixed a spur gear 4. The gear 4 meshes with a pinion 5 which is rotatable upon a stud shaft 6 projecting from the frame 1. Fixed to the pinion 5 is a fly wheel 80 pulley 7 adapted to be connected by a suitable endless belt, not shown in the drawing, with a convenient source of rotative power 85 to cause continuous revolution of the shaft 3. Fixed to the shaft 3 between the journal bearings 2, is a bit forming roll 8 in the periphery of which is formed a circumferential groove 9 the contour of which corre- 90

sponds to the form of the back of the cutting head of a mining machine bit.

Journalized in the bearings 10 of the main frame is a shaft 11 extending parallel with the shaft 3, and adapted to be rotated by movement of the hand lever 12 which projects upwardly to a position convenient to the hand of the operator. Formed on the shaft 11 between the bearings 10, is a cylindrical enlargement 13 which is eccentric of the bearings 10, and upon the cylinder 13 is journaled a hub 14. Projecting upwardly from the hub 14 is a radial arm 15 to the outer end of which is fixed the anvil 16 which is of circular curvature concentric with the cylinder 13. These parts are of such proportions that rotation of the shaft 11 will cause the eccentric 13 to lift the anvil 16 into forced engagement with the constantly revolving forming roll 8, the frictional effort of which tends to drive the anvil 16 forwardly about its axis 13. A spring 17 connected at one end to the main frame 1 and at the other end to the arm 18 formed 20 on the hub 14, tends to rotate the anvil 16 rearwardly and to retain it in its idle position in contact with the stop 19 when the frictional contact with the roll 8 is released. A resilient stop 20 fixed to the frame 1 is adapted to engage the forward end of the anvil 16 to limit its movement.

Fixed in a suitable recess of the anvil 16 is the die 21 which consists of a steel plate the upper edge 22 of which projects above the surface of the anvil and is shaped to conform to the contour of the groove 9 in the roll 8 with which it registers. The forward end of the plate 21 is shaped at 23 to form the face of a cutter bit in a manner which will hereinafter appear. The face 23 of the die 21 is transversely corrugated as shown in Figs. 7 and 10, to reduce the tendency of the metal to slip upon the die during the forming operation. Immediately in front of the die plate 21 is a socket 24 adapted to receive and hold in place the bit steel 25 during the operation of forming. When a suitably heated piece of steel is placed in the socket 24, and the lever 12 moved to lift the anvil 16 into contact with the roll 8, the frictional effort of the roll drives the anvil forward, carrying the bit steel 25 beneath the roller 8 to squeeze the metal against the die block and form the cutting head of the bit.

55 A plunger 26 slidably mounted in the socket 24, engages the lower end of the bit steel 25 to hold it in place, and a wedge 27 arranged to engage the lower end of the plunger 26 serves to limit its downward movement. 60 Fixed to the wedge 27 is a rearward extending rod 28 upon which is formed a screw thread engaged by a knurled head 29 mounted in the anvil casting and secured against longitudinal movement relative thereto. 65 The knurled head 29 is positioned convenient

to the hand of the operator, and by its rotation the wedge 27 may be moved forward and backward to adjust the position of the plunger longitudinal of the socket 24, thereby adapting the machine to the formation of bits of different lengths.

70 A bell crank 30, pivotally mounted upon a stud 31 fixed to the machine frame 1, is provided with a downwardly projecting arm 32 and a horizontal projecting arm 33, and is normally maintained in its idle position by a stop 34 formed on the machine frame 1 which engages the rearward face of the downwardly projecting arm 32. A pin 35 projecting laterally from the anvil casting, 75 is adapted to engage the arm 32 of the bell crank when the anvil approaches the forward limit of its movement, causing the horizontally projecting arm 33 to move upwardly into contact with the finger 36 of the plunger 26, to lift said plunger and thereby eject the bit steel 25 from the socket. As the bit 25 moves upwardly it is engaged by a spring 37 and forced laterally into the chute 38 by 80 which the bits are conducted away from the machine.

85 In order that the bits may be accurately positioned in the mining machine chain, we have provided means for cutting a nick in the bit shank at the depth to which it should extend into the socket of the cutter chain. This nicking device consists of a tool 39 attached to a vertical shaft 40 journaled in a bearing 41 of the machine frame. These parts are so proportioned and positioned that when the nicking tool 39 stands in one position of its angular adjustment about the axis of the shaft 40 it will engage the corner of the bit steel 25 to cut a notch therein. Fixed to the shaft 40 is a crank arm 42 connected by a rod 43 with a similar crank arm 44 fixed to a horizontally disposed shaft 45. A tension spring 46, attached at one end to the machine frame and at the other end to a second arm 47 which is also fixed to the shaft 45, 100 tends to rotate the nicking tool 39 to its operative position, and to resiliently hold it in that position. An arm 48 is fixed to the shaft 45, and to this arm is fixed a roller 49 adapted to engage the anvil 16 as it moves forwardly, and through the connections above described, to rotate the nicking tool 39 into its idle position at one side of the path of the cutter bits 25. These parts are so proportioned and arranged that, as soon as the nicking tool 39 has nicked the corner of the bit, said tool will be moved aside, out of the path of bit 25, to prevent further interference with its movements.

105 When new bits are formed from rolled bar stock it is desirable that the end of the steel be somewhat reduced to facilitate forming under the roll 8. For this purpose we have provided a squeezing device comprising an eccentric 50, formed on the projecting end of 110

the shaft 4, and fitted with an eccentric rod 51. To the lower end of the eccentric rod 51 is fixed a die block 52 adapted to cooperate with a stationary die 53 fixed to the side of the machine frame 1.

5 In the manufacture of the new bits, steel bars of suitable cross section are first cut into suitable lengths, and these pieces are heated by any preferred method, to a temperature suitable for working. As each piece is taken from the heating furnace its end is inserted between the dies 52 and 53 to be pointed preliminary to the final rolling operation. The bit steel 25 is then inserted, with its pointed end upward in the sockets 24 of the anvil. The knurled head 29 may then be manipulated to cause the proper amount of steel to project from the socket 24. By movement of the lever 12 the anvil is elevated into contact with the roll 8 and driven forward thereby carrying the bit steel beneath the roll 8 by which its metal is squeezed against the face of the die 23, accurately forming the cutting head of the bit. As the bit is carried beyond the 25 roll 8, the nicking tool 39 places a nick in its side to indicate the depth to which it should be inserted in the socket of the mining machine chain, after which the ejecting mechanism discharges the finished bit from the socket 24 onto the chute 38 in the manner above described.

In the mechanism above described we have provided a relatively small and inexpensive machine, convenient and economical of operation, whereby cutter bits may be accurately and expeditiously formed, and by which bits worn in service may be sharpened and renewed.

What we claim is:—

40 1. In a bit forming machine, the combination with a power driven continuously revolving roll having a continuous peripheral forming face, of an anvil mounted adjacent said roll and having a surface adapted to frictional engagement therewith whereby said anvil may be caused to move relative to said roll, and a die carried by said anvil to the rear of its initial point of engagement with said roll adapted to cooperate with said roll 45 at all peripheral points thereof to form a cutting head upon a suitably disposed bit steel as and for the purpose set forth.

2. In a bit forming machine, the combination with a supporting frame, of a continuously revolving roll mounted in fixed position upon said frame, a shaft spaced from and extending parallel to the axis of said roll and journaled in bearings of said frame, a cylindrical enlargement formed on said shaft eccentric to said journaled bearings, an anvil pivotally mounted upon said cylindrical enlargement and having an arcuate surface concentric therewith, means to rotate said shaft to cause said eccentric to move said arcuate surface into frictional engagement with said

roll to cause rotary movement of said anvil about said cylindrical enlargement, stops arranged upon the frame to limit rotary movement of said anvil in either direction, and means to move said anvil rearwardly upon the interruption of said frictional engagement as and for the purpose set forth. 70

3. In a bit forming machine, the combination with a supporting frame, of a continuously revolving roll mounted in fixed position upon said frame, a shaft spaced from and extending parallel to the axis of said roll and journaled in bearings of said frame, a cylindrical enlargement formed on said shaft eccentric to said journal bearings, an anvil pivotally mounted upon said cylindrical enlargement and having an arcuate surface concentric therewith, means to rotate said shaft to cause said eccentric to move said arcuate surface into frictional engagement with said roll 75 to cause rotary movement of said anvil about said cylindrical enlargement, and a spring to rotate said anvil rearwardly upon the interruption of said frictional engagement as and for the purpose set forth. 80

4. In a bit forming machine, the combination with a supporting frame, of a continuously revolving roll mounted in fixed position upon said frame, a shaft spaced from and extending parallel to the axis of said roll 85 and journaled in bearings of said frame, a cylindrical enlargement formed on said shaft eccentric to said journal bearings, an anvil pivotally mounted upon said cylindrical enlargement and having an arcuate surface concentric therewith, and means to rotate said shaft to cause said eccentric to move said arcuate surface into frictional engagement with said roll as and for the purpose set forth. 90

5. In a bit forming machine, the combination with a supporting frame, of a continuously revolving roll mounted in fixed position upon said frame, a shaft spaced from and extending parallel to the axis of said roll and journaled in bearings of said frame, a cylindrical enlargement formed on said shaft eccentric to said journal bearings, an anvil pivotally mounted upon said cylindrical enlargement and having an arcuate surface concentric therewith, means to rotate said shaft to cause said eccentric to move said arcuate surface into frictional engagement with said roll to cause rotary movement of said anvil about said cylindrical enlargement, and a stop arranged to limit forward movement of said anvil as and for the purpose set forth. 105

6. In a machine of the class described, the combination with a revolving roll adapted to form one side of a cutting head, of a die plate having a surface adapted to form the other side of the cutting head, means to hold a bit steel in suitable relation with said die and roll during the forming operation, and means upon the forming surface of said die to pre- 110

vent the slippage of the metal of the bit steel during the forming operation as and for the purpose set forth.

7. In a machine of the class described, the combination with a revolving roll adapted to form one side of a cutting head, of a die plate having a surface adapted to form the other side of the cutting head, means to hold a bit steel in suitable relation with said die and roll during the forming operation, and transversely extending grooves in the forming surface of the die adapted to prevent slippage of the metal of the bit steel during the forming operation as and for the purpose set forth.

8. In a machine of the class described, the combination with means to move a bit steel along a predetermined path, of means effective to form a cutting head upon said bit steel as it travels along said path, and other means effective during said travel of said bit steel along said path to nick it as and for the purpose set forth.

9. In a machine of the class described, the combination with means to move a bit steel along a predetermined path, of means effective to form a cutting head upon said bit steel as it travels along said path, of a nicking tool normally positioned in said path adapted to engage said bit steel to nick it, and means to move said nicking tool out of said path after the nicking operation as and for the purpose set forth.

10. In a machine of the class described, the combination with means to move a bit steel along a predetermined path, of means effective to form a cutting head upon said bit steel as it travels along said path, a nicking tool resiliently held in position in said path adapted to engage said bit steel to nick it, and means to move said nicking tool out of said path after the nicking operation as and for the purpose set forth.

11. In a machine of the class described, the combination with means to move a bit steel along a predetermined path, of means effective to form a cutting head upon said bit steel as it travels along said path, a shaft rotatably mounted adjacent said path, a nicking tool carried by said shaft and adapted in one position of rotary adjustment to extend into said path to engage said bit steel to nick it, and means to rotate said nicking tool about its axis of said shaft after the nicking operation as and for the purpose set forth.

12. In a machine of the class described, the combination with means to move a bit steel along a predetermined path, of means effective to form a cutting head upon said bit steel as it travels along said path, a shaft rotatably mounted adjacent said path, a nicking tool carried by said shaft adapted in one position of rotary adjustment to extend into said path to engage said bit steel to nick it, and

automatically acting means to rotate said nicking tool out of said path after the nicking operation as and for the purpose set forth.

13. In a machine of the class described, the combination with a bit forming device, of a bit holding device adapted to move a bit steel relative to said forming device during the forming operation, of a nicking tool in the path of said bit steel adapted to nick it, and means actuated by said bit holding device to move said nicking tool out of the path of said bit steel after the nicking operation as and for the purpose set forth.

14. In a machine of the class described, the combination with a bit forming device, of a bit holding device adapted to move a bit steel relative to said forming device during the forming operation, of a shaft rotatably mounted adjacent the path of said bit steel, a nicking tool carried by said shaft and adapted to extend into the path of said bit steel to nick it, and means actuated by said holding device adapted to move said nicking tool out of the path of said bit steel after the nicking operation as and for the purpose set forth.

15. In a machine of the class described, the combination with a bit forming device, of a bit holding device adapted to move a bit steel relative to said forming device during the forming operation, of a shaft rotatably mounted adjacent the path of said bit steel, a nicking tool carried by said shaft adapted to extend into the path of said bit steel to nick it, and a lever adapted to be engaged by said bit holding device to rotate said nicking tool about the axis of said shaft as and for the purpose set forth.

16. In a machine of the class described, the combination with a bit forming device, of a bit holding device adapted to move a bit steel relative to said bit forming device during the forming operation, means to eject said bit steel from said holding device after the forming operation, and resilient means to deflect said bit steel laterally of said holding device when ejected as and for the purpose set forth.

17. In a machine of the class described, the combination with a bit forming device, of a bit holding device adapted to move a bit steel relative to said forming device during the forming operation, means to eject the said bit steel from said holding device after said forming operation, and a spring adapted to engage said bit steel as it is being ejected from said holding device to deflect it laterally thereof as and for the purpose set forth.

18. In a machine of the class described, the combination with a bit forming device, a holding device adapted to move a bit steel relative to said forming device during the forming operation, means to adjust the bit steel relative to the holding device, and automatically acting devices adapted to eject said

bit steel from said holding device after the forming operation as and for the purpose set forth.

19. In a bit forming machine, a reciprocable member having an upwardly open socket for receiving a blank, an abutment in the socket, and means automatically actuated during the movement of said member for displacing the abutment upwardly, whereby the bit is ejected from the socket.

20. In a bit forming machine, a reciprocable member having an upwardly open socket for receiving a blank, an abutment in the socket, an arm pivoted to a fixed element adjacent the member, means for automatically rocking said arm during the movement of said member, said arm being adapted in its rocking to engage the abutment for displacing the latter whereby the bit is ejected from the socket.

21. In a bit forming machine, a driven shaft, a rotating die thereon, said die having a continuous forming face, a die operatively movable relative to said rotating die, an arcuate support for said movable die, said support being pivoted at its arc center, and means for radially displacing said arcuate support into engagement with said rotating die to initiate movement of the support and its associated die.

22. In a machine of the class described, a power drive, a bit holding device, means operated by the power drive to eject a bit upwardly from said holding device, and means to deflect the ejected bit laterally of said holding device.

23. In a machine of the class described, the combination with a bit forming device, of a holding device for a bit steel, means to move one of said devices relative to the other to form the bit, and means automatically actuated by the moving device subsequent to the forming operation to eject the bit, said means including a lever mounted on said other device and tripped by the moving device.

24. In a machine of the class described, the combination with a bit forming device, of a holding device for a bit steel, said holding device including an upwardly open socket to receive the bit steel and a movable abutment forming the bottom of the socket, means to reciprocate one of said devices relative to the other to form the bit, and means automatically actuated by the reciprocating device subsequent to the forming operation to move the abutment to eject the bit upwardly, said means including a lever tripped by the moving device.

25. In a bit forming machine, the combination with a power driven continuously revolving roll having a continuous peripheral forming face, of an anvil pivotally mounted adjacent said roll and having an arcuate surface concentric with its pivotal support

adapted for frictional engagement therewith, whereby said anvil may be caused to move relative to the roll about its axis, and a die carried by said anvil to the rear of its initial point of engagement with said roll adapted to cooperate with said roll at all peripheral points thereof to form a cutting head upon a suitably disposed bit steel.

In testimony whereof we have hereunto set our hands.
